SUPPORT STAND FOR AN AIR SPRAYING CONTAINER

Oliver W. Hildebrand, Florissant, Mo., assignor to Wirecraft Mfg. Company, St. Louis, Mo.

Filed Apr. 9, 1970, Ser. No. 22,354

Term of patent 7 years

Int. Cl. D6—99

U.S. Cl. D33—3

FIG. 4

FIG. 1

FIG. 2

FIG. 3

FIG. 5

FIG. 1 is a side elevational view of a support stand for an air spraying container showing my new design.

FIG. 2 is a front view thereof.

FIG. 3 is a side elevational view on the side opposite that shown in FIG. 1 thereof.

FIG. 4 is a top plan view thereof.

FIG. 5 is a bottom plan view thereof.

I claim:

The ornamental design for a support stand for an air spraying container, as shown.
